(57) CLAIM

The ornamental design for a corset, as shown and described.

DESCRIPTION

FIG. 1 shows a top plan view of the corset;
FIG. 2 shows a rear elevation view of the corset;
FIG. 3 shows a bottom plan view of the corset;
FIG. 4 shows a front elevation view of the corset;
FIG. 5 shows a right side elevation of the corset;
FIG. 6 shows a left side elevation of the corset; and,
FIG. 7 shows a perspective view of the corset.
In the drawings, broken lines have been used to illustrate stitch lines and to illustrate "Best Back" and "m'brace your body" text of the labels. The stitch lines form part of the claimed design. The "Best Back" and "m'brace your body" text of the labels form no part of the claimed design.
